BACK PACK FRAME

Vincent C. Tyrrell, 3728 W. 170th St., Torrance, Calif.

Filed Oct. 31, 1960, Ser. No. 62,669

Term of patent 14 years

(Cl. D87—5)

The dashed line showing in FIG. 1 is for illustrative purposes only.

I claim:

The ornamental design for a back pack frame, as shown and described.
